UNITED STATES PATENT OFFICE.

WILLIAM CRAINE, OF BROOKFIELD, NEW YORK.

BOTTOM-DISCHARGE SILO.

1,165,760.

Specification of Letters Patent. Patented Dec. 28, 1915.

Application filed September 14, 1914. Serial No. 861,700.

To all whom it may concern:

Be it known that I, WILLIAM CRAINE, a citizen of the United States, residing at Brookfield, in the county of Madison and 5 State of New York, have invented a new and useful Bottom-Discharge Silo, of which the following is a specification.

The device forming the subject matter of 10 this application is a silo, and one object of the invention is to improve the wall construction of the silo.

Another object of the invention is to provide a novel conveyer mechanism adapted 15 to remove the ensilage from the silo without opening the silo, the conveyer mechanism being adapted to move transversely of the axis of the silo, thereby to remove the ensilage throughout practically the entire 20 transverse area of the silo, to the end that the ensilage may feed down readily by its own weight, as a portion of the ensilage is removed from the bottom of the silo.

It is within the scope of the invention to 25 improve generally and to enhance the utility of devices of that type to which the present invention appertains.

With the above and other objects in view which will appear as the description proceeds, the invention resides in the combination 30 and arrangement of parts and in the details of construction hereinafter described and claimed, it being understood that changes in the precise embodiment of the invention herein disclosed can be made with- 35 in the scope of what is claimed without departing from the spirit of the invention.

In the accompanying drawing:—Figure 1 shows the invention in fragmental vertical section; Fig. 2 is a cross section; Fig. 3 is a 40 fragmental horizontal section taken through the conveyer support; Fig. 4 is a section taken on the line 4—4 of Fig. 3; Fig. 5 is a fragmental side elevation showing the wall construction of the silo; Fig. 6 is a horizontal sectional detail illustrating a portion 45 of the structure depicted in Fig. 5; Fig. 7 is a fragmental elevation showing a modified form of wall construction; Fig. 8 is a cross section showing a portion of the structure 50 delineated in Fig. 7.

The silo herein disclosed comprises a base 1 fashioned from any desired material, and upon the base 1 is superposed the body of the silo. The body of the silo includes a 55 plurality of upright staves 2, the longitudi-

nal edges of which are in contact, the staves being fashioned from wood. Surrounding the staves 2 is a filler 3 which may be made of paper. About the filler 3 and inclosing the staves 2 closely are hoops 4 which may be made of wood. The hoops 4 extend at right angles to the staves 2 and each hoop 4 is a separate unit. The transverse edges of the hoops 4 are in contact with each other. Each hoop is divided, and the ends of each hoop are connected by cover plates 5 which may be fashioned from metal, securing elements 6 being employed for connecting the cover plates 6 with the ends of the hoops 4. In place of the hoops 4, metallic bands 7 may be employed, the ends of the bands 7 being overlapped as shown at 7^a, these overlapped ends 7^a being united by securing elements 8, as clearly shown in Fig. 8.

Located within the body portion of the silo and extended inwardly from the body portion of the silo are approaching wings 9 which may be grooved in their inner edges as shown at 10 to receive door sections 11. 80 The wings 9 may be connected by rungs 12, to form a ladder. Obviously, the wings 9 and the adjacent portion of the wall of the silo define a compartment within the contour of the silo, the wall of the silo being devoid of openings adapted for the removal of the ensilage, the ensilage being removed by a conveyer mechanism which will be described hereinafter.

If desired, a small door 14 may be located 90 adjacent the bottom of the silo, not for the purpose of removing ensilage, but merely to give access to the conveyer mechanism hereinafter described.

In the base 1 of the silo, there is formed 95 a cavity 15 having an outwardly extended mouth 16. Disposed in the mouth 16 of the base is a box-like casing 17 including a top plate 18 the outer edge of which is formed into a rack 19.

The invention includes a conveyer support 20 in the form of a block and comprising a circular body 21 having an extension 22 which projects outwardly. The conveyer support 20 is provided at the center of the 105 circular body 21 with shafts 23 which are journaled in the upper and lower portions of the casing 17, to the end that the conveyer support 20 may swing horizontally. Extended through the body portion 21 of the 110

conveyer support 20 and through the extension 22 thereof is a bore 24. A portion of the bore 24 which lies in the extension 22 is open at its bottom but normally is closed by a bottom plate 25, as clearly shown in Fig. 1.

Attached to the forward or outer end of the extension 22 is a bracket 26 having wings 27 engaging the side faces of the extension 22 and overlapped on top of the extension.

10 The bracket 26 carries a bearing 28. Upstanding from the bracket 26 is an arm 29 which overhangs the top of the forward end of the extension 22. In the arm 29 is journaled an upright shaft 30 provided at its upper end with a head 31 equipped with one or more openings 32 adapted to receive a lever or the like whereby the shaft 30 may be rotated. At its lower end, the shaft 30 carries a pinion 33 which meshes into the rack 19.

20 The conveyer which is carried by the conveyer support 20 may be of any desired form. In the present instance, the conveyer is shown as comprising a shaft 34 journaled in the bearing 28 and provided with a crank 35 or other suitable means whereby the shaft may be rotated. At its inner end, the shaft carries an auger 36 lying partly in the bore 24 of the conveyer support and extended into the cavity 15. A closure 37 is pivoted as shown at 38 to the side wings 27 of the bracket 26. When the conveyer 36 is in operation, the closure 37 is turned downwardly to form a chute, as shown in Fig. 1, but when the conveyer 36 is not in use, the closure 37 is turned up into a vertical position so as to close the outer end of the bore 24 of the conveyer support 20 partially, thereby to prevent air from entering the silo.

In practical operation, the conveying auger 36 is rotated through the medium of the crank 35 or its mechanical equivalent, the ensilage within the silo being drawn outwardly. When the shaft 30 is rotated, the pinion 33 thereon, meshing into the rack 19 formed upon the outer edge of the top plate 18 of the casing 17, will effect a horizontal swinging of the conveyer support 20 on its shafts 23. Thus, the auger 36 may be made to sweep horizontally from one side of the cavity 15 to the other. Thus, the ensilage may be removed throughout the entire horizontal extent of the cavity and when a quantity of ensilage has been removed in this manner, the superposed ensilage will

move downwardly by gravity and fill the cavity.

It is to be observed that it is unnecessary to form doors in the silo for the purpose of removing the ensilage, the door 14, as aforesaid, being used merely to give access to the conveyer mechanism.

Having thus described the invention, what is claimed is:

1. The combination with a silo having a sub-structure, of a tubular carrying member mounted on the sub-structure to swing transversely of the silo; a rigid auger journaled in the carrying member, the outer end of the auger being accessible from the outside of the silo; means on the outer end of the auger for rotating the auger; and means for imparting a swinging movement of the carrying member, whereby the auger will swing transversely of the axis of the silo. 65

2. The combination with a silo having a sub-structure, of a tubular carrying member mounted on the sub-structure to swing transversely of the silo; a rigid auger journaled in the carrying member, the outer end of the auger being accessible from the outside of the silo; means on the outer end of the auger for rotating the auger; and means for imparting swinging movement to the carrying member, whereby the auger will swing transversely of the axis of the silo, the sub-structure being provided with a recess in 80 which the auger is mounted to move transversely, that portion of the sub-structure which lies beyond the opening constituting a means for upholding a part of the contents 85 of the silo, to prevent an undue pressure on the auger. 90

3. The combination with a silo, of a conveyer mounted to swing transversely of the ensilage in the silo and beneath the material 95 in the silo; a means for swinging the conveyer transversely; and a means for imparting an ensilage-retracting movement to the conveyer; both of said means being located outside of that portion of the silo which receives the ensilage. 100

In testimony that I claim the foregoing as my own, I have hereto affixed my signature in the presence of two witnesses.

WILLIAM CRAINE.
